(57) **CLAIM**

The ornamental design for a tilt adjustable display interface bracket, as shown and described.

DESCRIPTION

FIG. 1 is a front perspective view of a tilt adjustable display interface bracket according to the invention;

FIG. 2 is a rear elevation view of the tilt adjustable display interface bracket depicted in FIG. 1;

FIG. 3 is a front elevation view of the tilt adjustable display interface bracket depicted in FIG. 1;

FIG. 4 is a top plan view of the tilt adjustable display interface bracket depicted in FIG. 1;

FIG. 5 is a bottom plan view of the tilt adjustable display interface bracket depicted in FIG. 1;

FIG. 6 is a side elevation view of the tilt adjustable display interface bracket depicted in FIG. 1; and,

FIG. 7 is an opposing side elevation view of the tilt adjustable display interface bracket depicted in FIG. 1.
